SHOE SEWING MACHINE

James M. Matheu, Queens Village, N. Y., assignor to United Shoe Machinery Corporation, Borough of Flemington, N. J., a corporation of New Jersey

Application April 22, 1939, Serial No. 269,435

11 Claims. (Cl. 112—62)

The present invention relates to shoe sewing machines, and more particularly to improvements in machines for sewing the upper to the sole of a shoe or slipper while unsupported on a last.

- 5 In sewing a shoe or slipper off the last, it is common practice to provide means for supporting the inner surface of the shoe sole against the thrust of the work penetrating instruments, particularly where curved instruments are employed.
- 10 The usual manner of sewing is to hold the margin of the upper against the edge of the sole and to sew through the upper and sole edge, the seam preferably lying in a channel formed about the sole without having the stitches pass through the
- 15 inner surface of the shoe. Heretofore it has been necessary, while sewing in this manner, to present a shoe to the sewing machine with the sole in approximately vertical position where the operation of the sewing instruments is partly obscured
- 20 from the operator's view by the upper. Accordingly, unless the upper has already been temporarily secured to the sole, it is difficult to manipulate the upper properly while the sewing progresses. If the upper is already secured to the
- 25 sole, a more complicated machine is required for the sewing operation inasmuch as a support for the inner surface of the sole may only be provided by means of an elongated horn entering the ankle opening of the shoe.

30 The objects of the present invention, therefore, are to provide a simple and easily operated machine for sewing shoes while unsupported on a last in which the operator's line of sight is not obscured by the shoe upper and with which a better 35 grade of work may be produced without the exercise of unusual skill or ability.

With these and other objects in view, the present invention contemplates the provision in a curved hook needle sewing machine of the type in which the hook portion of the needle operates through an arc below the center of needle curvature, of means passing between the margin of the upper and the edge of the sole in advance of the point of operation of the needle to support the shoe sole substantially horizontally where both margin of the upper and point of emergence of the needle from the sole is visible from the front of the machine at all times. As herein-after described, the supporting means is in the form of a Z-shaped guide, the oblique portion of which extends between the margin of the shoe upper and the edge of the sole, and the lower sole supporting portion of which is horizontal. Preferably the machine is provided with a channel guide actuatable towards and from the sole to

hold the sole more effectively. To assist the operator in presenting the shoe properly, according to a further feature of the invention, the machine is equipped with an edge gage operating on the upper along the seam line beyond the line of needle operation, such gage being of advantage whether the channel guide is actuatable towards or from the sole guide or stationarily mounted on the machine frame.

Other features of the invention consist in certain devices, combinations, and arrangements of parts hereinafter described and claimed, the advantages of which will be readily understood from the following description taken in connection with the accompanying drawings.

In the drawings Figure 1 is a view in side elevation of a portion of the shoe sewing machine embodying the features of the present invention; Figure 2 is a detail plan view, partly in section, taken along the line 2—2 of Figure 1, illustrating the operation of the stitch-forming and work-feeding devices including the sole guide; Figure 3 is a view in side elevation of the parts illustrated in Figure 2; and Figure 4 is a detail view of the sole guide indicating the positions of the sole and upper of a shoe being operated upon.

The machine illustrated in the drawings is a curved hook needle chainstitch machine for sewing the margin of a shoe or slipper upper 2 to the edge of a sole 4 while unsupported on a last, the parts being directed manually towards the sewing point during operation of the machine. The machine, except as hereinafter described, is similar to that disclosed in U. S. Letters Patent to Eppler No. 1,108,560 of August 25, 1914, the patented machine being arranged to sew the upper to the sole of a shoe while supported on a last. In addition to the curved hook needle indicated at 6, the machine is provided with an awl or feed point 8, a looper 10, and a channel guide 12. Like the patented machine, the illustrated machine is also provided with a welt guide, secured to a carrier 13 pivotally mounted at 14 on the frame of the machine and actuatable towards and from the work by means of a link 15 connected with a slide 16 on which is slidably mounted a clutch box 18. To actuate the carrier, the clutch box is connected by means of a link 20 to a cam lever 22. The lever 22 as well as the mechanisms for actuating the stitch-forming devices are operated from cams on a main sewing shaft 24. The slide 16 is pressed yieldingly in a direction to move the carrier 13 towards the work by a spring 26 around a stud 28 on the frame. To assist in guiding the shoe during sewing as in the patented ma-

chine, a bunter is mounted on a slide 30 arranged to be pressed yieldingly in a forward direction as by a spring 32 connected at one end to the frame and at the other end to the slide 30. Both slides 16 and 30 are locked intermittently during sewing and released to accommodate successive positions of the work. To lock the slides 16 and 30, a pair of clutch rolls 34, 36 are provided which press respectively against the slides, when engaged by a wedge member 38 carried by a cam actuated lever 40. As thus far described, the machine is the same as the machine of the patent referred to.

In the illustrated machine, the hooked portion 15 of the curved needle 6 which penetrates the work and which carries the loop of thread is arranged to oscillate about a stud 42 through an arc, the active length of which is substantially beneath the center of the stud, the curvature of the 20 needle being concentric therewith. The advantage of such an arrangement with this type of machine is that the point of the needle, during the work penetrating stroke, first engages the upper and holds it in position along a shoulder or 25 rib at the edge of the sole, and the needle emerges from a channel, indicated at 44 (Fig. 2) formed in the sole, in clear view of the operator, so that improper operation of the machine may quickly be detected. Heretofore in sewing a shoe while 30 unsupported on a last, with machines of this type, it has been found desirable to secure the upper margin entirely around the edge of the sole before sewing, and to support the inside of the upper by means of a horn extending through the 35 ankle opening of the shoe so that the parts will not be dispensed during sewing.

According to the present invention, the necessity for employing a horn in this type of machine has been eliminated, the sole being supported by 40 a Z-shaped sole guide 46 mounted on the slide 30 which formerly supported the bunter in the patented machine. To locate the sole guide in proper relation to the stitch-forming devices, it is secured to a block 48 which, in turn, is bolted 45 to the forward end of the slide 30. In use, the oblique portion of the Z extends between the margin of the upper and the edge of the sole in advance of the point of needle operation, and the lower portion supports the inner surface of the 50 sole beneath the needle stud 42. To support the sole edge rigidly beneath the needle, that portion of the sole guide inside the shoe extends laterally beyond the plane of the needle. Between the oblique portion of the guide and the upper portion, there is a space for the upper margin which 55 aids in guiding the upper properly and forms a gage for the edge of the upper. The spring 32 and the locking roll 36 cause the sole guide 46 to be pressed yieldingly against the sole edge 60 while being fed and to be locked during the retraction of the threaded needle from the work.

Instead of securing the upper margin entirely around the edge of the sole before sewing, as in prior machines of this type, with the present machine the upper and sole may be presented to the machine separately until the first few stitches are inserted and the upper is then directed to the guide 46 in proper relation to insure that the upper margin will overlap the sole edge. It may 65 be desirable where a separate lining in addition to the leather upper is used to cement the lining to the upper or to loosely attach the upper to the sole at a number of spaced points as by wire staples 47 (Fig. 2). When so attached, the 70 oblique portion of the sole guide 46 between the 75

upper and sole edge causes the staples to be withdrawn as the parts are separated by the guide without interfering with the feeding movement of the shoe.

To impart feeding movements to the sole and upper, the feed point 8 and the channel guide 12 are mounted on a feed slide 51, the feed point acting to penetrate the work and to move into line with the needle during each sewing cycle and to withdraw as the needle enters the work. During the back feeding movement of the channel guide, the sole guide is still locked and the channel guide 12 is retracted a short distance from the channel 44 in the sole so as to avoid any tendency of displacing the work, the channel guide mechanism being the same as in the patented machine and including a cam lever 49. The channel guide cooperates with the sole guide at other times to hold the shoe in proper relation to the needle and awl while the sole guide is locked in position.

To assist further in supporting the shoe being operated upon, there is secured to the carrier 13 an edge gage 50 contacting the upper along the line of the seam beyond the point of operation of the needle. The edge gage is locked and unlocked by the wedging member 38, and the locking roll 34 simultaneously with the locking and unlocking of the sole guide. The mechanism for retracting the slide 16 and the edge gage 50 acts in each sewing cycle just before the feeding movement of the feed point so that the edge gage offers no resistance as the shoe is advanced a stitch length.

The nature and scope of the invention having been indicated, and a specific embodiment having been described, what is claimed is:

1. A machine for sewing the upper to the sole of a shoe while unsupported on a last having, in combination, stitch-forming and work-feeding devices including a curved needle formed with a hooked work penetrating portion arranged to oscillate through an arcuate path, the active length of which is substantially beneath the center of needle curvature, and means passing between the margin of the upper and the edge of the sole in advance of the point of needle operation to support the sole approximately horizontally in the path of the needle.

2. A machine for sewing the upper to the sole of a shoe while unsupported on a last having, in combination, stitch-forming and work-feeding devices including a curved needle formed with a hooked work penetrating portion arranged to oscillate through an arcuate path, the active length of which is substantially beneath the center of needle curvature, and a Z-shaped sole guide beneath the center of needle curvature, the oblique portion of which guide extends between the margin of the upper and the edge of the sole in advance of the point of needle operation, and the lower portion of which supports the inner surface of the sole approximately horizontally with the edge of the sole in the path of the needle.

3. A machine for sewing the upper to the sole of a shoe while unsupported on a last having, in combination, stitch-forming and work-feeding devices including a curved needle formed with a hooked work penetrating portion arranged to oscillate through an arcuate path, the active length of which is substantially beneath the center of needle curvature and a Z-shaped sole guide beneath the center of needle curvature, the oblique portion of which guide extends between the margin of the upper and the edge of the sole

in advance of the point of needle operation, and the lower portion of which extends laterally beneath the needle to support that portion of the sole engaged by the needle.

5. 4. A machine for sewing the upper to the sole of a shoe while unsupported on a last having, in combination, stitch-forming and work-feeding devices including a curved needle formed with a hooked work penetrating portion arranged to 10 oscillate through an arcuate path, the active length of which is substantially beneath the center of needle curvature, means passing between the margin of the upper and the edge of the sole in advance of the point of needle operation to 15 support the sole approximately horizontally in the path of the needle, and a channel guide actuatable towards and from the sole support means to hold and release the sole during each sewing cycle.
20. 5. A machine for sewing the upper to the sole of a shoe while unsupported on a last having, in combination, stitch-forming and work-feeding devices including a curved needle, a sole guide passing between the margin of the upper and 25 the edge of the sole to support the sole in the path of the needle, a channel guide cooperating with the sole guide to hold the sole opposite the sole guide in advance of the point of needle operations, and an edge gage operating on the 30 upper along the seam line beyond the point of needle operations.
6. A machine for sewing the upper to the sole of a shoe while unsupported on a last having, in combination, stitch-forming and work-feeding 35 devices including a curved needle, a sole guide passing between the margin of the upper and the edge of the sole to support the sole in the path of the needle, a channel guide, and an edge gage operating on the upper along the seam line 40 beyond the point of needle operations.
7. A machine for sewing the upper to the sole of a shoe while unsupported on a last having, in combination, stitch-forming and work-feeding devices including a curved needle, a sole guide 45 passing between the margin of the upper and the edge of the sole to support the sole in the path of the needle, a channel guide, an edge gage operating on the upper beyond the point of needle operations, a carrier on which the edge gage is 50 mounted arranged for movement towards and from the upper, means for locking the edge gage intermittently against movement away from the upper, and means for actuating the channel guide during sewing operations to hold the sole in position while the edge gage is locked.
8. A machine for sewing the upper to the sole of a shoe while unsupported on a last having, in combination, stitch-forming and work-feeding devices including a curved needle, a sole guide 55 passing between the margin of the upper and the edge of the sole to support the sole in the path of the needle, a channel guide, an edge gage 60 operating on the upper beyond the point of needle operations, a carrier on which the edge gage is mounted arranged for movement towards and from the upper, means for locking the edge gage intermittently against movement away from the upper, means for actuating the channel guide during sewing operations to hold the sole in position while the edge gage is locked.
9. A machine for sewing the upper to the sole of a shoe while unsupported on a last having, in combination, stitch-forming and work-feeding 15 devices including a curved needle, a sole guide passing between the margin of the upper and the edge of the sole to support the sole in the path of the needle, a channel guide, an edge gage 20 operating on the upper beyond the point of needle operations, a carrier on which the edge gage is mounted arranged for movement towards and from the upper, means for locking the edge gage intermittently against movement away from the upper, a feed point, mechanism for actuating the channel guide during sewing operations to hold and release the sole opposite the sole guide, means for actuating the edge gage to press yielding against the upper and to be locked while 25 the sole is held by the channel guide, and means for retracting the edge gage during feeding movement of the feed point.
10. A machine for sewing the upper to the sole of a shoe while unsupported on a last having, in combination, stitch-forming and work-feeding 30 devices including a curved needle, a sole guide, passing between the margin of the upper and the edge of the sole to support the sole in the path of the needle, a channel guide, a feed slide on which the channel guide is mounted, 35 mechanism for actuating the channel guide to hold the sole during feeding movement of the feed slide and to release the sole during back feeding movement of the feed slide, and means for actuating the sole guide to press yielding 40 against the sole edge during feeding movement of the feed slide and for locking the sole guide during back feeding movement.
11. A machine for sewing the upper to the sole of a shoe while unsupported on a last having, in combination, stitch-forming and work-feeding 45 devices including a curved needle, a sole guide, said guide being Z-shaped with the oblique portion extending between the margin of the upper and the edge of the sole with the lower portion 50 supporting the sole in the path of the needle and with the upper portion forming with the oblique portion a guide for the margin of the upper, and a channel guide cooperating with the sole 55 guide to hold the sole.

JAMES M. MATHEU.

CERTIFICATE OF CORRECTION.

Patent No. 2,204,901.

June 18, 1940.

JAMES M. MATHEU.

It is hereby certified that error appears in the printed specification of the above numbered patent requiring correction as follows: Page 2, first column, line 36, for the word "dispensed" read --displaced--; and that the said Letters Patent should be read with this correction therein that the same may conform to the record of the case in the Patent Office.

Signed and sealed this 27th day of August, A. D. 1940.

Henry Van Arsdale,
Acting Commissioner of Patents.
